TILING

David Broadwin, New York, N. Y.

Application March 31, 1938, Serial No. 199,193

2 Claims. (Cl. 72—18)

My invention relates to tiling and more particularly to a tile provided with improved means for insuring a firm and unyielding connection between the tile and a wall or other base.

5 One of the objects of my invention is to provide a tile unit which is prepared prior to installation and which, by such preparation, is afforded a rear surface perfectly adapted for anchorage to a wall.

10 Another object of my invention is to provide a tile unit which is equipped with anchorage means on its rear surface but without unduly adding to its expense of manufacture, thereby insuring a cheap and economical as well as an 15 efficient tile unit.

Other objects of my invention will be apparent from the following description, it being understood that the foregoing statement of the objects of my invention is intended to explain

20 and not to limit it in any manner.

Fig. 1 is a rear view of my tile unit partly broken away.

Fig. 2 is a section along the line 2—2 of Fig. 1.

25 Fig. 3 is a section along the line 3—3 of Fig. 1. Referring to the drawing, 10 represents the tile which is generally of a vitreous material, such as glass, and which may be colored or transparent.

The tile is provided with ribs 11 over its rear 30 surface. A tile of this construction is well known in the art and is ordinarily applied to a wall by a bonding material such as a plaster of Paris composition, the ribs 11 affording anchorage means for the bonding material. However, it 35 is common knowledge that due to a variety of causes, the tile often separates from the bonding material destroying its utility.

According to my invention, a coat of ordinary 40 paint 12 is applied to the ribbed surface and this paint 12 is preferably of an oil type, which oxidizes and solidifies on exposure to air, gradually becoming converted from an elastic substance to a hard, adhering coat. Since nearly every known 45 paint is of this type and reacts as described, a specific composition is unnecessary as long as the paint displays a binding quality as herein-after explained.

Over this coat of paint 12 and before it hardens, a layer of ordinary sand is applied either by spraying or pouring. The sand may be either fine or coarse, the size being immaterial as long as it is not smaller than 0.05 mm. diameter separated by means of sieves, or as large as gravel. Generally, a size approximating 0.15 mm. diameter separated by means of sieves is suitable.

5 As the paint hardens, the sand is more or less firmly embedded therein and the surplus sand is merely shaken off. When the paint has fully hardened the tile with its sand backing is ready for use or may be stored or transported as desired.

It is apparent that a tile thus prepared has a 15 rear surface that is admirably adapted for co-operation with a plaster mass to anchor the tile to a base since the roughest surface possible may be obtained by these means.

In addition to the provision of means to retain 20 the sand, the paint 12 may serve another function. Should the glass tile 10 be transparent and uncolored, the paint will be visible therethrough and novel aesthetic advantages may be combined with utilitarian advantages by my 25 process.

I have shown a preferred embodiment of my 30 invention, but it is apparent that numerous changes and omissions may be made without departing from its spirit.

I claim:

1. A tile unit comprising a tile having a corrugated rear surface, a coating of paint applied to said corrugated surface, and a layer of sand covering said coat of paint, the granules of said sand layer projecting beyond the outer surface of the coating of paint.

2. A tile unit comprising a tile having an irregular rear surface, a layer of paint applied to said rear surface, and a layer of sand having its 40 granules partially embedded in said layer of paint and substantially covering said layer of paint.

DAVID BROADWIN.
